COATING MACHINE

Wiltie I. Gladfelter and Carl C. H. Hauger, Philadelphia, Pa., assignors to Crown Cork & Seal Company, Inc., Baltimore, Md., a corporation of New York

Application July 16, 1940, Serial No. 345,832

18 Claims. (Cl. 91—45)

The present invention relates to apparatus for handling and treating articles, such as containers and the like, during the original manufacture thereof or at other times. More particularly, the invention provides an apparatus that will transfer a line of containers from an infeed conveyor and move them along a predetermined path, where the containers are coated and then deposit the coated containers upon an outfeed conveyor.

It is an object of the invention to provide an apparatus that will uniformly, completely and efficiently coat a great plurality of articles in a minimum period of time.

It is a further object of the invention to provide a machine of this class that will operate continuously over long periods of time, without interruption for adjustment or repair, whereby the containers in a container manufacturing line may be coated at the same speed as the other operations in the line are performed.

It is a further object of the invention to provide novel means for handling the containers, to prevent scratching thereof prior to the coating operation, and to prevent marring or smearing of the coated surfaces, during and after the coating operation. To this end, it is an object of the invention to provide transfer dials which firmly grip the containers and prevent rubbing of the side walls of the containers with guide rails or the like.

It is a further object to provide novel means for supporting the containers during the coating operation, so that all surfaces of the containers are exposed a plurality of times to the coating instrumentalities. A further object is to provide improved means for supporting the containers and rotating them about their own axes, as they are moved along a predetermined path past the coating instrumentalities, such as spray guns or the like, and to provide means for non-rotatably supporting the containers at the infeed and outfeed stations.

It is a further object to provide continuously operating spray-coating means, which will not become clogged or otherwise rendered inefficient by continuous operation. To accomplish this object, the invention provides a plurality of spray guns, or the like, and means for periodically and alternately rendering the individual guns operative, so that each gun operates for a predetermined time, followed by a period of rest, during which the gun is automatically cleared for subsequent efficient operation.

Other and further objects and advantages of

the invention will be apparent from the following description of a specific embodiment of the invention, reference being had to the accompanying drawings which are illustrative of the invention.

In the drawings:

Figure 1 is a plan view of the apparatus, with the table enclosing hood removed for the sake of clarity.

10 Figure 2 is a vertical view, partly in section and partly in elevation, taken substantially on line 2—2 of Figure 1.

Figure 3 is an enlarged horizontal section and plan view, taken on line 3—3 of Figure 2.

15 Figure 4 is a horizontal section on line 4—4 of Figure 2.

Figure 5 is a similar view taken on line 5—5 of Figure 2.

20 Figure 6 is a horizontal sectional detail of an air valve structure.

Figure 7 is a fragmentary elevation of the device of Figure 6.

Figure 8 is a vertical section taken through the infeed and outfeed dials looking toward the machine of Figure 1.

Figure 9 is an enlarged elevation, partly in section, showing a preferred spray gun supporting means.

30 Figure 10 is a plan view of the construction shown in Figure 9.

Figure 11 is an enlarged vertical section taken substantially on line 11—11 of Figure 1, showing a preferred form of article supporting chuck with the parts in one position.

35 Figure 12 is a partial elevation and partial section showing the elements of Figure 11 in another position.

Figure 13 is a horizontal section taken substantially on line 13—13 of Figure 12.

40 Figure 14 is an enlarged plan view, partly in section, of a preferred form of outfeed dial.

Figure 15 is a similar view of an infeed dial.

45 Figures 16 and 17 are vertical sectional views of certain elements incorporated in the aforesaid dials.

Figure 18 is a fragmentary vertical sectional detail taken on line 18—18 of Figure 1.

50 Figure 19 is a plan view of a preferred form of hood assembly.

Figure 20 is a view, half in section and half in elevation, taken substantially on line 20—20 of Figure 19.

Figure 21 is a fragmentary elevation of the hood taken from the opposite side thereof.

Figure 22 is an elevation of a closure member for the front face of the hood, and

Figure 23 is a top plan view of the closure member.

General description

Although not confined to such use, the machine of the present invention is particularly adapted to apply a coating of lacquer or varnish to the exterior surfaces of containers of the type disclosed in the application of Calleson and Calleson, Serial No. 334,876, filed May 13, 1940. In the embodiment illustrated, the containers have previously had the bottom end members seamed thereon, but it should be understood that the coating machine may be used to coat the containers before the end members are applied. As illustrated in Figure 1, the containers are moved along an infeed conveyor 20 which, in the embodiment illustrated, comprises an articulated chain, but since the conveyor forms no part of the invention it need not be described in detail. An infeed dial 21 of special construction, herein-after described, transfers the containers from the conveyor 20 to chucks 22 associated with a rotatable table 23. The containers are carried by the chucks along a circular path past spray guns 24, 25 to receive a coating of lacquer or varnish from the guns, the chucks and the containers being rapidly rotated about their vertical axes during this movement by means herein-after described. After the cans have been coated, they are removed from the supporting chucks 22 by a special out-feed dial 26, herein-after described in detail, and transferred to an outfeed conveyor 27, which, in the preferred embodiment, is a continuation of the infeed conveyor 20.

Supporting frame and main drive

The machine base comprises an upwardly opening casing 30 having a bottom wall 31, a front wall 32, side walls 33, 34 and an upstanding, arcuate, rear end wall 35, reference being had to Figures 2 and 5. Integral downwardly projecting bosses 36 receive legs 37 which may be adjustably mounted in pedestals 38 or the like. The bottom and side walls of the casing are provided with suitable reinforcing ribs 39 to impart the desired strength and rigidity to the main frame. The upper open end of the main frame 32 is closed by a bed plate 40, having its lateral edges 41 supported upon the upper edges of the side and end walls, as indicated in Figure 2. The bed plate, likewise, is provided with radially disposed, tapering reinforcing ribs or flanges 42, extending toward the edges thereof. The casing and bed plate are provided with a plurality of aligned apertures, in which vertical shafts 43, 44, 45 and 46 are journaled for rotation. Shafts 43, 44 and 45, respectively, carry the table 23 and the infeed and outfeed dials 21, 26, while shaft 46 carries a driving pinion 47 at its upper end and is connected at its lower end to an appropriate driving motor 48 by any suitable speed reducing mechanism, not shown.

Shafts 44 and 45 additionally carry spur gears 49, 50, in mesh with a large gear 51 secured to the table actuating shaft 43, whereby the infeed and outfeed dials and the table are rotated in predetermined ratio, at the same peripheral speed, the gears 49, 50 being equal in radius to the transfer dials and the gear 51 being equal in radius to the distance from the center of the table to the centers of the can-supporting chucks. Driving gear 47 is in mesh with the gear 49.

whereby rotation is imparted to all of the gears and shafts.

The table and chuck assemblies

As shown in Figure 2, the table 23 is supported by thrust bearings 55, disposed between a collar 56, carried by the bed plate 40 and an inverted cup member 57 which supports the hub of the table and encloses the bearing.

The table is preferably a unitary casting comprising a disc-like portion 23, a central hub 60 keyed to the shaft 43, a plurality of radial reinforcing ribs 61, and a downturned, marginal reinforcing flange 62. Inwardly of the flange, there are a plurality of circumferentially spaced openings 63 defined by cylindrical flanges 64, projecting above and below the table, reference being had to Figures 2, 11 and 12. The openings in the table receive the chuck assemblies 22, described below.

Above the table 23 and forming a part of the assembly, there is positioned a pan structure, comprising two semicircular sections 65, centrally supported upon the hub 60 and provided with flanged openings 66, embracing the chuck assemblies 23, as shown in Figures 11 and 12. Only a fragment of one pan section 65 is illustrated in Figure 1, the remainder being removed for the sake of clarity, but it will be understood that the pan is coextensive in area with the table and is spaced thereabove.

The table and the elements carried thereby are enclosed by a hood structure represented generally at 52 and described below, a preferred form of hood being shown in Figures 19-23. The hood is provided with openings in its side wall for the spray projected inwardly by the exteriorly supported guns and with entrance and exit openings for the containers adjacent the infeed and outfeed dials.

The chuck assemblies 22 which receive the containers from the infeed dial 21, described below, are illustrated in Figures 11 and 12 and reference is made thereto. Each assembly comprises a stationary sleeve 67 disposed within the opening 63 and having an outwardly projecting flange 68 overlying one of the cylindrical flanges 64 of the table. The sleeve is preferably clamped in place by a ring 69 below the opening in the table and secured by bolts 70. Upon the flange 68 of the sleeve 67, there is secured by any appropriate means, a second sleeve member 71, closely fitting within the flanged opening 66 of the pan 65, the sleeve being provided at its upper end with an inwardly and upwardly tapering portion 72, providing a seat for the double seam 73 at the bottom end of the container 76. Of course, if the bottom end member has not been seamed to the container, the seat 72 will engage the margins of the outwardly turned seaming flange of the can body.

The first stationary sleeve 67 and the ring 69 carry the outer races of bearing assemblies 78, 79, spaced apart by a collar 80 and in which a hollow spindle 81 is journaled. The spindle carries at its lower end a pulley or sheave 82, while an oil packing 83 is interposed between the hollow spindle and the ring 69.

A rod 84, slidably mounted for longitudinal movement in the hollow interior of the spindle 81, is urged upwardly by a coil compression spring 85, disposed in an enlarged portion of the bore and bearing upwardly against the central sleeve 75 of a spindle head 88, the latter being provided

with a downturned skirt 89, disposed between the stationary sleeves 71 and 67. An appropriate packing 90 provides a seal between the sleeve 67 and the skirt 89, while the head 88 as a whole is secured to the rod or spindle 84 by a centrally disposed bolt 91. A ring 92 of highly magnetized metal is bolted to the head 88, with a suitable gasket or spacer 93 interposed. Thus, the hollow spindle 81 and the pulley 82 are mounted for rotation relative to the sleeves 67 and 71, but are restrained against longitudinal movement with respect thereto by bearings 78, 79 and clamping ring 69, while the shaft 84 which rotates with the hollow spindle and forms a part of the spindle assembly, together with the skirted head 88 and the magnetized ring 92 are mounted for limited longitudinal movement with respect to the stationary sleeves and the can seat 72. The means for controlling the longitudinal movements of these parts will now be described.

Adjacent each chuck holding aperture 63, there is a depending bracket 95 having at its lower end a substantially radially disposed bore 96 provided with a bearing sleeve 97 in which a rock shaft 98 is journaled. An arm 99, carrying a cam following roller 100, is secured to one end of the rock shaft and a shifting fork 101 is secured to the other end thereof. The shifting fork carries inwardly projecting pins 102, 103 at its ends, disposed in a peripheral groove 104, in a shifting collar 105 fast upon the lower end of the shaft 84. The cam following roller 100, journaled upon a pin 106, is disposed beneath a downwardly facing cam 107 carried by an upwardly projecting, arcuate bracket 108, supported by the bed plate 40 of the machine and extending between the infeed and outfeed positions, as indicated in Figures 1, 2 and 11.

Thus, as the table rotates, the cam rollers 100 associated with the several chuck assemblies, pass under the cam 107, as they approach the outfeed station. The cam forces the arm 99 downwardly and, by means of the rock shaft 98, lowers the shifting fork 101, the grooved shifting collar 105, the central shaft 84 of the spindle assembly, and the head 88 and the magnetized ring 92. Hence, the parts are drawn downwardly to the position shown in Figure 11, when they reach the infeed station, and containers may be positioned by the infeed dial upon the seats 72, to be supported thereby along the margins of the containers. As the rotation of the table continues, the rollers 100 pass from under the end of the cam 107, with the result that the springs 85 force the heads 88 and the associated parts upwardly, to the position shown in Figure 12, so that the magnetized rings 92 are projected upwardly into the concave lower ends of the associated containers to support the same a slight distance above the relatively stationary seats 72. When in this position, the chuck spindles and the containers supported thereby are rapidly rotated about their own axes as the table conveys them past the spray guns 24, 25.

The chuck spindle drive

As pointed out above, each spindle sleeve 81 carries adjacent its lower end, a pulley 82, the centers of the several pulleys being arranged in a circle about the table axis as a center. As shown in Figures 4 and 8, sheaves 110, 111 are journaled for rotation on the infeed and outfeed spider supporting shafts 44, 45, these sheaves being disposed outwardly with respect to the circu-

lar path of movement of the spindle pulleys 82. An endless belt 112 is trained about the sheaves 110, 111 and about all of the pulleys 82 on the opposite side of the machine, as shown in Figures 1, 3 and 4. A tension sheave 113, carried by a shaft 114, may be adjusted relative to the sheaves 110, 111 to apply the desired tension to the belt. The sheaves 110, 111 have spur gears 115, secured to their lower faces, in mesh with spur gears 116, journalled upon counter-shafts 117 and having smaller spur gears 118 secured to their lower faces, the latter being in mesh with gears 119 pinned to the spider shafts 44, 45. The gear ratio, as indicated in Figure 8, is preferably such that the sheaves 110, 111 rotate substantially four times as fast as the spider shafts 44, 45, in the same direction as the shafts. Thrust bearings 120, 121 carry the load of the gear train, the sheaves 110, 111 and the infeed and outfeed spiders.

The belt 112 is continuously driven at a relatively rapid speed during the operation of the machine. As the chuck assemblies leave the infeed station, with cans supported upon the fixed seats 72, the rotatable spindles are projected upwardly, as described above, to support the cans above the seats. When the chucks arrive substantially at the position indicated by the chuck 22a, in Figures 1 and 3, the pulleys 82 are brought into contact with the belt 112, whereupon the pulleys, the spindles and the cans supported thereby are rapidly rotated. This rotation continues during the movement of the chucks and cans along their circular path of movement, until the pulleys 82 move away from the belt, prior to reaching the outfeed station, about at the position of the chuck indicated at 22b in Figures 1, 3 and 4. Hence, the chucks are free to come to rest. As the cam rollers 100 move under the cam 107, the rotatable spindles and the magnetic rings 92 are lowered, whereupon the containers are again supported upon the stationary seats 72. At this time, the outfeed dial, hereinafter described, grasps the cans and removes them from the coating machine.

The spray guns and their control means

As the containers are rotated and carried along the path of movement defined by the rotation of the table, their exterior surfaces are sprayed by the guns 24 or 25, or by other guns similarly positioned adjacent this path of movement. As indicated in Figures 1, 2, 9 and 10, these guns are of well known type, comprising a spray nozzle 125, a varnish or liquid inlet 126, an atomizing air inlet 127 and a second air inlet 128 in the nature of a control line leading to a needle valve actuating cylinder (not shown) in the body 129 of the gun. Since spray guns of this type are well known and do not, specifically, form a part of the present invention, their structural details will not be described. When the air in the line 128 is cut off, the needle valve is projected to closed position, to interrupt the flow of atomizing air and the flow of lacquer or varnish, as well as to clear the lacquer or varnish delivery passage. In guns of this type, this passage must be closed and cleared occasionally, to prevent clogging thereof and to avoid variations in the character of the spray produced.

Automatic means are provided for performing this function. As shown in Figures 2 and 5-7, the air line 128 from the gun 25 leads to a valve 133 carried beneath the machine casing 31, while

The infeed and outfeed dials

the corresponding line from the gun 24 leads to a similar valve 134. A cam 135, carried by the lower end of the table shaft 43, serves to actuate the valves periodically and substantially in alternation, to effect corresponding operation of the 5 spray guns.

As shown in Figures 6 and 7, each valve assembly comprises a casing 136 having an inlet passage 137 connected to a source of compressed air and an outlet passage 138 connected to the pipe 10 leading to the inlet of the spray gun. Spring-pressed valve bodies 139, 140 are mounted for reciprocating movement in the aforesaid passages, on pins 141, 142 which extend through the casing 136 into proximity to a cam following lever 143, pivoted at 144 and having a cam following roller 145 on one end. A tension spring 146, connected to the other end of the lever, normally urges the same into the position shown in full lines in Figure 6, where the valve 139 in the passage leading from the source of compressed air is closed by its spring, while the valve 140 in the delivery passage is open, thereby permitting a back flow of air through that line from the gun to relieve the pressure in the gun through the exhaust port 147, in the side of the valve casing 136. When the cam 135 shifts the lever to its other position, the valve 139 is opened, thereby permitting a flow of compressed air from the source, and the exhaust port 147 is closed by the valve 140, thereby causing the compressed air to flow to the gun, to open the needle valve and render the gun operative.

The cam profile and the angular relation of the valve assemblies are preferably such that there is a slight overlap between the time when one valve opens and the other closes. In other words, in their normal cycle of operation, the guns are operating slightly longer than not. Hence, there is no chance that any can will pass through the machine without being thoroughly sprayed by one gun or another.

It must be understood that the invention is not limited to the use of only two guns, as any desired number can be used, positioned at any desired circumferential location relative to the path of movement of the cans.

The rear, arcuate wall 35 of the main machine casing is turned inwardly, as indicated at 150 and is provided with an arcuate groove 151 in its upper face. Arcuate track members 152, 153 (Fig. 9) are secured along and project inwardly over the margins of the groove and bolts 154, 155 having enlarged heads are disposed in the groove beneath the tracks. Each pair of bolts 154, 155 extend upwardly through a block 156, slidably mounted on the tracks 152, 153 and nuts 157, 158 securely clamp the blocks in place, in any desired circumferential position thereon. Laterally and upwardly projecting rods 159 are secured in hollow bores in the blocks by set screws 160 or the like. The spray guns 24, 25 are mounted for universal adjustment on the upper ends of the rods 159 by clamps 165, each rotatably adjustable about the axis of the rods, and by arms 166 projecting laterally from the clamps, about which the guns are rotatably adjustable, being secured in place by set screws 167. The circumferential position of the guns relative to the tracks 152, 153 may be changed at will by shifting the blocks 156, while the elevation and angle of spray projection may be adjusted by changing the position of the guns relative to the rods 159.

As stated above, the containers are transferred from the conveyor chain 20 to the table by an infeed dial 21 and are removed from the table and replaced upon the conveyor by an outfeed dial 26. Since both dials have many features of construction in common, only one will be described and the differences between the two then pointed out. The dials, mounted upon the upper ends of the rotating shafts 44, 45, each comprise a central hub 170 secured by bolts 171 to a flange 172 of a sleeve 173 carried by the shaft, the bolts being threaded into the flange 172 and disposed in elongated, arcuate slots 174 in the hub member, whereby the hub may be angularly adjusted relative to the supporting sleeve 173. The hub 170 is preferably a unitary casting having an upper annular portion 175, in which the aforesaid slots are arranged and in which vertical sleeves 176 are formed, the upper portion terminating at its outer margin in an annular edge or shoulder 177. Vertically disposed webs 178, depending from the upper portion 175, carry, at their lower ends, an inwardly projecting annular flange 179, provided with apertures 180 aligned with the sleeves 176. A lower ledge 181, positioned below the upper ledge 177, has threaded bolt holes 182 therein, disposed in alignment with similar holes 183 in the upper ledge 177. Upper and lower dial elements are secured to the upper and lower ledges 177, 181 by bolts threaded in the holes. As shown in Figures 1 and 15, the upper and lower dial elements 184, 185, associated with the infeed dial 21, are provided with outwardly projecting arms 186 which are curved forwardly in the direction of rotation of the dial and which define article receiving pockets 187. The outfeed dial includes upper and lower dial plates 188, 189, which are somewhat similar in construction, but which have arms 190 curved rearwardly with respect to the direction of rotation.

Vertically disposed rock shafts 191, journaled for rotation in the sleeve 176 and aperture 180 in the hub 170, carry outwardly projecting movable arms 192, 193 disposed at an elevation substantially midway between the rigid arms 184, 185 and 188, 189, respectively. Each vertical rock shaft 191 carries a rearwardly projecting arm 194, upon the end of which there is rotatably mounted a cam following roller 195 disposed in engagement with a cam 196 formed on the peripheral face of a flange 197 associated with a stationary sleeve 198 surrounding the dial supporting shaft. Sleeves 199, pinned to the upper ends of the rock shafts 191, carry laterally projecting arms 200, which are connected to tension springs 201, the latter being in turn connected to a ring 202 mounted on the upper end of the dial shaft.

A raised platform 205 extends around the front of the machine beneath the infeed and outfeed dials and is provided with down-turned ends 206, 207, secured to the bed plate 40. The cams 196 are supported upon the platform 205, as shown in Figures 2 and 8, while the conveyor chain 20 (Fig. 18) moves in a channel member 208 thereon, beneath stationary article supporting plates 209, the latter being supported in spaced relation above the platform 205 by collars 210. A pivoted guide 211 (Fig. 1) is adapted to yield outwardly to actuate a safety device to stop the machine 75 in case of a jam. Stationary guide rails 212, 213

forming a part of a unitary guide bracket 214 are also provided.

It should be noted that the fixed arms 188, 189 of the outfeed dial each carry a pair of rearwardly projecting, adjustable screws 215 which are provided with sharply pointed ends, adapted to make only pin-point contact with the freshly coated containers. Similarly, the movable arms 193 are each provided with a sharply pointed, adjustable screw 216, to engage the opposite side of the cam.

The table enclosing hood assembly

Referring to Figures 19-23, the hood assembly 52 is carried by upwardly projecting, vertical rods 220, 221, supported upon the main frame of the machine. An upper flue member 222 has, at its upper end, an annular angle iron reinforcing member 224 to which laterally projecting supporting bars 225, 226 are welded, the bars being supported upon the upper ends of the rods 220, 221. The flue 222 may be open at its upper end, as indicated, or, if desired, it may be connected to an appropriate duct leading to the outside or to a collector for the volatile solvents used in the varnish or lacquer spraying material.

The hood assembly includes a lower table enclosing section 223, having an upper frusto-conical portion terminating at its upper end in an inwardly turned flange 227 normally resting upon a packing ring 228, carried by an angular flange 229 secured to the outer face of the flue 222, whereby a substantially air-tight seal is provided between the flue and the lower section when the latter is in its normal, lowered position. At its lower margin, the frusto-conical portion of the hood merges into a portion having a vertically disposed arcuate wall 230, having openings 231, 232, 233 therein, through which the sprays from the exteriorly disposed spray guns may be projected. In the embodiment illustrated, each opening is substantially 57° in circumferential extent, but it must be understood that the openings may be closed or reduced in length by appropriate closure members.

At the juncture between the vertical and the frusto-conical portions, there is positioned an arcuate, angle iron reinforcing member 234, to add strength to the assembly. A second arcuate reinforcing angle iron 239 is disposed adjacent the bottoms of the openings 231-233, while a third arcuate, angle iron 235 is welded to the lower edge of the side wall 230, with its horizontal flange extending inwardly and supporting a horizontal floor strip 236, carrying at its inner edge a vertical flange 237, adapted to assume a sealing relation to the table, as shown in Figure 20. Vertically disposed angle irons 238 or U-section channel members may be welded to the arcuate, angle irons 235, 239 and to the side wall adjacent the margins of the openings, to impart the desired rigidity to the hood.

The front face of the hood section 223 is disposed upon a vertical plane, which is a chord of the frusto-conical and arcuate portions, thereby providing a vertical front wall 240 on the upper portion and a similar wall 241 on the lower portion. The wall 241 defines an enlarged opening 242, adapted to be closed by a flat closure plate 243 having apertures 244 therein which are received by hooks 245, for ready removal and replacement. The closure plate 243 has a rearwardly projecting reinforcing angle strip 246 welded to its rear face adjacent its upper end, and is provided with openings 247, 248 adjacent 75

its lower edge, the openings being closed by special entrance and exit assemblies.

These assemblies comprise vertically disposed plates having arcuate inner portions 249 arranged concentric to the table axis, radial entrance or exit portions 250 and outer angularly disposed outer end portions 251, the edges of the portions 249 and 251 being welded to the adjacent edges of the openings 247, 248. Horizontal, top closure plates 252 are welded to the upper edges of the vertical plates and to the upper margins of the openings 247, 248. Each radial plate portion 250 has an opening 255 therein, substantially corresponding in outline to the container being treated, so that there is little or no chance that spray from the spray guns will be projected entirely across the table and outwardly through the small spaces between the containers and the margins of the openings.

20 The lower section 223 of the hood assembly is vertically movable relative to the flue section 222. Brackets 255 provided with apertures 256 embracing the vertical rods 220, 221 are secured to the lower hood section 223 and are provided with openings 257 for the reception of hooks or bolts associated with counter-balanced lifting chains or the like, not shown. Adjacent their lower ends, the rods 220, 221 carry inwardly projecting stop plates 258, 259, which support the lower, arcuate reinforcing angle iron 235. A handle 260 secured to the hood may be employed to raise the hood section 223 when it is desired to gain access to any of the parts associated with the rotatable container-supporting table.

Operation

40 The cam 196, associated with the infeed spider, is so shaped that, as each pair of upper and lower stationary dial arms approach a container brought into the dial pocket by the infeed conveyor, the spring 201 of the associated movable arm swings the arm rearwardly with respect to the direction of rotation of the dial to clamp the container firmly between the fixed and movable arms. The articles are thus firmly held against relative rotation in the dial pockets. The movements of the dial and the table are so related that each pocket passes directly over an article receiving chuck on the table, in exact alignment 45 therewith. At this instant, the cam 96, in engagement with the rollers 95, swings the movable arms 192 in the opposite direction, against the tension of the springs 201 to release the containers and position the same accurately upon 50 the seats 72 of the table chucks, the spindle heads 88 and magnetic rings 92 being at that time in their lowered position. As the chucks leave the infeed station, the cam following rollers 180 pass from under the cam 101, whereupon the springs 85 project the heads 88 upwardly to lift the containers from the stationary seats 72, the containers being firmly held upon the heads by the magnetized rings 92. As the table continues 55 its rotation, the chucks carry the containers through the entrance opening 256 into the interior of the hood section 223. Immediately thereafter, the pulleys 82 successively come into contact with the driving belt 112, whereby the spindles and the containers supported thereby 60 are rapidly rotated. The containers are moved past the spray guns 24, 25, at least one of which is in operation, as controlled by the central cam 135. The containers receive a uniform, even coating of varnish or lacquer and are carried 65 around on the table, outwardly through the exit

opening 255 of the hood, to the discharge station. During this movement, the pulleys 82 move out of contact with the driving belt 112 and the spindles and the containers may come to rest. The cam rollers 100 move under the stationary cam 107 adjacent the outfeed station, with the result that the end members 88 and the magnetized rings 92 are lowered and the containers are supported non-rotatably upon the seats 72.

At this point, the containers are moved into the pockets of the outfeed dial, substantially into contact with the pin-points 215. The cam 196, associated with the outfeed dial, permits the movable arms to swing forwardly under the influence of the springs 201 to closed position, so that the pin-points 216 carried thereby engage the cans and transfers them from the machine. The cans are gripped by these sharply pointed elements 215, 216 and firmly held against rubbing or smearing until they reach the outfeed conveyor 27, whereupon the cam 196 moves the movable arms rearwardly to release the cans and to permit them to be carried away by the conveyor.

Although the invention has been described with considerable particularity by reference to the accompanying drawings, it must be understood that many changes in construction can be made and that the invention is not limited to the specific details shown and described, but covers all modifications coming within the scope of the appended claims and their equivalents.

We claim:

1. An article coating machine comprising a rotatable table, a plurality of rotatable, article holding chucks disposed circumferentially on the table, spray means supported in normally fixed position adjacent the path of movement of the chucks, means for continuously rotating the table, means for rotating the chucks about their axes as they move past the spraying means, and means for changing the effective, operative position of said spraying means along said path.

2. An article coating machine comprising a rotatable table, a plurality of rotatable, article holding chucks arranged circumferentially on the table and each comprising a receiving member fixed with respect to the table and another member carried by the table for rotation with respect to the receiving member, means for feeding articles to the chucks, means for discharging coated articles therefrom, means for rotating the table, spraying means positioned adjacent the path of movement of the articles and disposed to spray the surfaces thereof, means for rotating the second-mentioned members of the chucks and the articles about their axes as they move past the spraying means, and means for positioning the articles on the fixed receiving members of the chucks to arrest the rotation of the articles at the discharge position.

3. An article coating machine comprising a rotatable table, a plurality of article holding chucks arranged circumferentially thereon, means for rotating the table, a plurality of relatively stationary spray guns positioned adjacent the path of movement of the chucks, means for rotating the chucks as they move past the spraying guns, and automatic means operating in timed relation to the rotation of the table for periodically clearing and rendering inoperative one gun while another continues in operation.

4. An article coating machine comprising a

rotatable table, a plurality of rotatable article holding chucks arranged circumferentially on the table, two spray guns positioned adjacent the path of movement of the table and directed toward the path of movement of articles on the chucks, means for rotating the chucks and the articles as they are moved past the guns, and means controlled by the rotation of the table for periodically rendering each gun inoperative and for simultaneously operating the other gun, whereby no one gun operates continuously.

5. An article coating machine comprising a rotatable table, a plurality of rotatable, article holding chucks arranged circumferentially on the table, at least two air-operated spray guns positioned adjacent the path of movement of the table and directed toward the path of movement of the articles supported on the chucks, means for rotating the chucks and the articles as they pass said guns, an air valve for controlling the operation of each gun and cam means rotating in timed relation to the rotation of the table for actuating said air valves to cause the guns to operate substantially alternately.

6. An article coating machine comprising a rotatable table, article transfer means adjacent the path of rotation of the table, a plurality of chucks arranged circumferentially on the table and journaled for rotation on axes parallel to the table axis, a pulley on each chuck, a sheave rotatable about a fixed axis adjacent the article transfer means and spaced outwardly from a circle drawn through the centers of the chuck pulleys, a belt trained about said sheave and about the chuck pulleys on the opposite side of the table, whereby as the chucks approach said sheave and the transfer means they move out of driven relation to the belt and reengage the belt after they depart from the transfer means and the sheave, and coating means positioned adjacent a portion of the movement of the chucks where the pulleys are in engagement with the belt.

7. A coating machine comprising a plurality of article supporting chucks mounted for rotation about their own axes and for movement along a circular path, transfer means adjacent said path for delivering articles to and for removing articles from said chucks, pulleys associated with the chucks for movement therewith, sheave means positioned adjacent the transfer means and spaced outwardly from the path of movement of the pulleys, a belt trained about said sheave means and the pulleys on the opposite side of the circular path of movement of the chucks from the sheave means and the transfer means, whereby said pulleys move out of contact with the belt as the chucks approach the transfer means and reengage the belt as the chucks move away from the same, means for driving the belt to rotate the pulleys and the chucks when in contact therewith, and spray means positioned to coat the articles while the latter are being rotated by the chucks.

8. A coating machine comprising a table mounted for rotation about a vertical axis, infeed and outfeed dials rotatably mounted adjacent thereto, a plurality of vertical spindles arranged circumferentially in the table and journaled for rotation about their axes, article holding chucks and driving pulleys on the spindles, sheaves journaled for rotation coaxially with the infeed and outfeed dials, a belt trained about said pulleys and sheaves, means for rotating the table and the dials, means for rotating the

sheaves at a greater speed than the dials whereby as the pulleys leave the infeed dial they successively engage the belt and are rotated thereby, to rotate the chucks, and, as they approach the outfeed dial, they successively move out of contact with the belt, and spray means positioned to coat the articles while the latter are being rotated by the chucks.

9. A coating machine comprising a table mounted for rotation about a vertical axis, positively driven infeed and outfeed dials mounted upon rotatable shafts adjacent the table, a plurality of vertical spindles arranged circumferentially in the table and journaled for rotation about their axes, article holding chucks and pulleys on the spindles, sheaves journaled for rotation on the infeed and outfeed dial shafts, a belt trained about the pulleys and the sheaves, driving gears between the dial shafts and the sheaves for transmitting motion from the former to the latter at an increased speed to drive the belt and the pulleys, whereby, as the pulleys leave the infeed dial, they successively engage the belt and are rapidly rotated thereby and, as they approach the outfeed dial, they successively move out of contact with the belt, and spray means positioned to coat the articles while the latter are being rotated by the chucks.

10. A can coating machine comprising a rotatable table, infeed and outfeed dials adjacent thereto, a plurality of members fixed with respect to the table for supporting the lower ends of cans as they are successively placed thereon by the infeed dial, heads carried by the table and mounted for movement upwardly through the members to engage the bottoms of the cans and to lift the same above the members, means for so raising the heads, means for rotating the heads and the cans supported thereby when raised, means for coating the cans when so raised, and means for lowering the heads below the members to cause the cans to be non-rotatably supported by the members.

11. A can coating machine comprising a rotatable table having a plurality of members fixed with respect thereto for supporting the lower ends of cans, means for placing the cans on the members, magnetic heads carried by the table and mounted for movement upwardly through the members to engage the bottoms of the cans and lift the same above the members, means for rotating the heads and the cans supported thereby when raised, and means for coating the cans when in the last-mentioned position.

12. A can coating machine comprising a rotatable table having a plurality of circumferentially arranged openings therein and depending brackets adjacent the openings, can supporting spindles in the openings mounted for rotation about their axes and for axial movement relative to the table, shifting collars on the spindles having peripheral grooves therein, shifting forks pivotally mounted on the brackets and engaging the collars, a stationary cam track, cam following means operatively connected to said shifting forks, whereby, upon rotation of the table, the axial positions of the spindles are controlled by said cam and the cam following means, to support the cans for rotation at predetermined times, and means for coating the cans when so supported by said spindles.

13. A can coating machine comprising a rotatable table having a plurality of circumferentially arranged openings therein and depending brackets adjacent the openings, can supporting spindles in the openings mounted for rotation about their axes and for axial movement relative to the table, shifting collars on the spindles having peripheral grooves therein, shifting forks pivotally mounted on the brackets and engaging the collars, a stationary cam track, cam following means operatively connected to said shifting forks, whereby, upon rotation of the table, the axial positions of the spindles are controlled by said cam and the cam following means, to support the cans for rotation at predetermined times, and means for coating the cans when so supported by said spindles.

14. A can coating machine comprising a rotatable table having a plurality of circumferentially arranged openings therein and depending brackets adjacent the openings, can supporting spindles in the openings mounted for rotation about their axes and for axial movement relative to the table, shifting collars on the spindles, shifting forks pivotally mounted on the brackets and engaging the collars, a stationary cam track, and cam following means operatively connected to said shifting forks, whereby, upon rotation of the table, the axial positions of the spindles are controlled by said cam and the cam following means, pulleys on the spindles, a positively driven belt positioned to be engaged and disengaged by the pulleys during the rotation of the table to impart rotation to the spindles at predetermined times, and means for coating the cans while rotating with the spindles.

15. A can spraying machine comprising a rotatable table having a plurality of circumferentially arranged openings therein and surfaces concentric thereto for supporting the margins of the can ends, sleeves carried by the table for movement therewith and journaled for rotation in the openings, spindles carried by the sleeves for rotation therewith and for axial movement relative thereto, can end engaging heads carried by the spindles inwardly of said surfaces, means for projecting the spindles and the heads upwardly to raise the cans from said surfaces, spindle rotating means, means for connecting the spindles thereto when in the raised position, means for spraying the exterior surfaces of the cans while rotating, means operative thereafter for disconnecting the spindles from said spindle rotating means, and means for then lowering the heads out of contact with the cans to cause the cans to be non-rotatably supported by said surfaces.

16. An apparatus for spray-coating articles, such as containers and the like, comprising a rotatable table adapted to receive and convey the articles along a circular path, a stationary arcuate support adjacent the path of movement of the articles, a plurality of spray guns and adjustable mounting means connecting said guns to said arcuate support, whereby the positions of the guns may be changed circumferentially of said path.

17. An apparatus for spray-coating articles, such as containers and the like, comprising a rotatable table adapted to receive and convey the articles along a circular path, an arcuate track extending along the path of movement of the articles, blocks movable along the track, clamping means for holding the blocks in different positions on the track, for adjustment circumferentially of said path, a supporting bracket carried by each block, and a spray gun mounted on each bracket.

18. An apparatus for spray-coating articles, such as containers and the like, comprising a rotatable table adapted to receive and convey the articles along a circular path, a pair of spray guns adjacent the path of movement of the articles, a compressed air line leading to each gun, an air valve in each line controlling the operation of the associated gun, and a cam ro-

tatable with said table for controlling the positions of said valves and the operation of the associated guns, said valves being positioned relative to said cam so as to be rendered operative 5 substantially alternately.
